UNITED STATES PATENT OFFICE.

JUDSON DUNLOP, OF CAMBRIDGE, MASSACHUSETTS, ASSIGNOR OF ONE-HALF TO PORTER DUNLOP, OF SAME PLACE.

DESIGN FOR A PIE-PLATE.

SPECIFICATION forming part of Design No. 27,858, dated November 16, 1897.

Application filed September 25, 1897. Serial No. 653,058. Term of patent 7 years.

To all whom it may concern:

Be it known that I, JUDSON DUNLOP, a subject of the Queen of Great Britain, residing in Cambridge, in the county of Middlesex and State of Massachusetts, have invented and produced a new and original Design for Pie-Plates, of which the following is a specification, reference being had to the accompanying drawings, forming part thereof.

10 Figure 1 is a plan view of a pie-plate showing my new design. Fig. 2 is a central vertical section thereof.

As shown in the drawings, the leading or material feature of my design consists in the 15 shape of the raised edge of the plate or that portion which surrounds and extends up from the substantially flat bottom A. This circular edge or flaring side is formed up from the bottom A at a into the annular wall B, which 20 is slightly concave in cross-section. At B' a

downwardly-inclined flat annular bend C is produced, and at C' the edge of the plate is formed into the hollow annular trough D, concave in cross-section and constituting nearly or quite a half-circle. Thus the plain flat 25 bottom A is surrounded by the upwardly-extending and slightly-concave annular portion B, the downwardly-inclined flat portion C, and the concave or trough-shaped portion D, extending to the extreme edge, and all concentrically arranged.

Having described my invention, what I claim as new, and desire to secure by Letters Patent, is—

The design for a pie-plate, substantially as 35 herein shown and described.

JUDSON DUNLOP.
